EXTENSION HANDLE FOR CASKETS

Samuel M. Riddick, Canton, Miss., assignor to
Kittie B. Riddick, Canton, Miss.

Application December 15, 1931, Serial No. 581,215

1 Claim. (Cl. 16—112)

This invention relates to handles for caskets and the like, the general object of the invention being to provide an extension handle for the casket which is inexpensive to construct, and which has 5 considerable strength and which is movably connected to the casket so that when not in use will hang down alongside the casket and when in use will project therefrom.

This invention also consists in certain other 10 features of construction and in the combination and arrangement of the several parts to be hereinafter described fully, illustrated in the accompanying drawing and specifically pointed out in the appended claim.

15 In describing the invention in detail, reference will be had to the accompanying drawing wherein like characters denote like or corresponding parts throughout the several views, and in which:—

Figure 1 is a fragmentary side view of the casket 20 showing the improved handle attached thereto with part of the handle in section.

Fig. 2 is a vertical sectional view through Fig. 1.

In these views, the letter A indicates the side part of a casket and B indicates a hinge, one leaf 25 1 being fastened to the casket by the screws 2, and these screws are so placed that they enter different grains of the wood of the casket so as to greatly eliminate splitting of the wood.

A lug 3 is connected to the other leaf 4 of the 30 hinge, and the handle bar 5 is fastened to the lug by a screw or the like as shown at 6.

It will of course be understood that a number of hinges and lugs are used for connecting the handle bar 5 to the casket.

35 The upper end of the lug is slightly reduced in thickness and is formed with an end part 7 for engaging a part of the leaf 1 of the hinge. When the handle is in use so as to limit the upward movement of the parts as shown in Fig. 2, and 40 when the handle is not in use the same extends down parallel with the side of the casket.

A cover plate 8 is fastened to the side of the casket by the screws 9 and is formed with the

50 notch 10 through which the lower leaf 4 of the hinge extends. This plate covers the upper leaf 1 and the lower leaf 4 is hidden by the lug. In order to strengthen the handle bar 5 I groove the 55 same and place a bar 11 of steel or the like therein, and I connect the free end of the leaf 4 to said bar by a screw 12.

From the foregoing it will be seen that I have provided a simple form of bar handle for a casket, with means whereby the handle and the parts 60 associated therewith will lie alongside the casket when not in use, but which when in use will be spaced from the sides of the casket so as to enable the casket to be readily carried.

It is thought from the foregoing description 70 that the advantages and novel features of the invention will be readily apparent.

It is to be understood that changes may be made in the construction and in the combination and arrangement of the several parts provided that 75 such changes fall within the scope of the appended claim.

Having thus described my invention, what I claim as new is:—

In combination, a hinge having one leaf adapted 80 to be fastened to a side of a casket, with the second leaf depending from the first leaf, the lower end part of the second leaf being adapted to be fastened to a handle bar, a block fastened to the outer face of the second leaf and covering the 85 same, the lower end of the block abutting and fastened to the handle bar, the upper end of the block forming a shoulder for contacting the lower end of the first leaf to limit upward movement of the second leaf and handle bar, and a cover plate 90 adapted to be fastened to the side of the casket and covering the first leaf and having a notch in its lower part in which the lower portion of the first leaf and the upper portion of the second leaf are located, said notch receiving the upper portion 95 of the block.

SAMUEL M. RIDICK.
